United States Patent Office.

JOHN MOESSINGER, OF NEW YORK, N. Y.

Letters Patent No. 95,369, dated September 28, 1869.

IMPROVED READING-DESK

The Schedule referred to in these Letters Patent and making part of the same.

To all whom it may concern:

Be it known that I, JOHN MOESSINGER, of the city, county, and State of New York, have invented a new and improved Reading-Desk; and I do hereby declare the following to be a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is a plan or top view of the same.

Similar letters indicate corresponding parts.

This invention relates to a reading-desk, which is adjustable in a vertical and in a horizontal direction, so that the book supported by the desk can be accommodated in its position to the position of the person desiring to read. The platform supporting the book is made in two parts, which are connected together by a balance-lever, so that one rises when the other falls, and *vice versa*, and that the two parts of the platform will readily adapt themselves to the two halves of the cover of a book, placed open on the desk.

The platform is provided with adjustable slides, carrying the cover-holders and the leaf-holders, so that the desk can be readily adjusted to different sizes of books.

In the drawing—

The letter A designates a column, which rises from a base-plate, B, and which may either be near the end of the base-plate, or in the centre thereof, as may be considered most convenient.

The base-plate may be provided with a raised rim, so that articles placed thereon will not slide off, and may also be provided with shelves, to receive books, which are thus conveniently at hand, and also serve as additional weights to steady the reading desk.

The column A is bored out to receive a rod, C, which is adjustable in a vertical direction, by means of a set-screw, a, and which carries a head, D, through which passes a horizontal rod, E, which is adjustable by a set-screw, b.

The head D is also made adjustable by a set-screw, c.

The horizontal rod E forms the guide for a head, F, which supports the reading-desk G, and which is adjustable by a set-screw, d.

The rod E is made round, so that the reading-desk cannot only be moved on the same in a longitudinal direction, but it can also be turned to any desirable inclination, or adjusted in a horizontal position, as may be required.

The reading-desk proper is composed of two parts, each of which is connected to the head F by cross-

levers e, which allow the same to rise and fall, and said two parts are connected together by a balance-lever, H, so that if one rises, the other is compelled to fall, and *vice versa*.

The object of this construction of the reading-desk is to allow the same to adapt itself to the cover of the book, spread open on the same, as shown in fig. 1 of the drawing.

Each part of the reading-desk is provided with two slides f, which draw out in opposite directions from the ends of said parts, and which are fastened in the required position by set-screws g.

To the outer ends of these slides are secured transverse V-shaped arms h, which form the guides for slides i, carrying the cover-holders j, and the friction leaf-holders k.

By means of the slides f i, the cover-holders can be readily brought into the required position to catch and retain the cover of the book, spread on the desk, and the friction leaf-holders k can be made to bear with sufficient force on the edges of the leaves, to prevent them from turning over spontaneously.

In many cases, however, particularly if the desk is brought in an inverted position, it is desirable to have surface leaf-holders l, which overlap the leaves, and retain them securely in position.

These leaf-holders are secured to rods m, which rise from lateral slides n, and they are made in the form of weak springs, so that they can be readily forced back to release or admit the leaves.

When the surface leaf-holders l are used, the friction leaf-holders can be dispensed with.

It must be remarked, that instead of using the column A and platform B, the vertical rod C can be fitted into a screw-clamp, which may be screwed to a table or other piece of furniture.

What I claim as new, and desire to secure by Letters Patent, is—

1. The reading-desk G, constructed of two parts, united by a balance-lever, H, substantially as shown and described.

2. The end slides f, carrying the cover-holders j and friction leaf-holders k, either or both, in combination with the desk G, substantially as set forth.

3. The lateral slides n, carrying the surface leaf-holders l, in combination with the adjustable cover-holders j, and with the desk G, substantially as described.

This specification signed by me, this 11th day of August, 1869.

JOHN MOESSINGER.
